UNITED STATES PATENT OFFICE.

ROBERT V. MILLER AND JOHN ARVID MOLIN, OF YONKERS, NEW YORK.

LOCK ATTACHMENT FOR SOCKETS.

1,131,728.

Specification of Letters Patent. Patented Mar. 16, 1915.

Application filed May 8, 1914. Serial No. 837,135.

To all whom it may concern:

Be it known that we, ROBERT V. MILLER, a citizen of the United States of America, and a resident of Yonkers, Westchester county, and State of New York, United States of America, and JOHN A. MOLIN, a citizen of the United States of America, and a resident of Yonkers, Westchester county, and State of New York, United States of America, have invented certain new and useful Improvements in Lock Attachments for Sockets, of which the following is a specification, reference being had to the accompanying drawings, forming a part thereof.

Our invention relates to contact sockets and particularly to such as are adapted to receive a screw-threaded plug or base and to lock the inserted plug or base against unwarranted removal.

One object of our invention is to provide a particularly simple and improved locking device which shall effectively prevent the removal of a plug or base without the use of a suitable key, but which shall not at all interfere with the insertion of the plug or base.

Another object of our invention is to provide an attachment for standard Edison base lamp sockets which may very readily be applied to a socket without electrically connecting its casing to either of the socket terminals and which may be manufactured in large quantities at small cost.

Other objects and advantages of our invention will be set forth hereinafter, and in order that our invention may be thoroughly understood, we will now proceed to describe the same in the following specification and then point out the novel features thereof in appended claims.

Figure 1 is a partially sectional elevation of a lamp socket equipped with our invention, a lamp being shown in position as inserted in the socket. Fig. 2 is a sectional elevation on the line 2-2 of Fig. 1, and Fig. 3 is a sectional plan view on the line 3-3 of Fig. 1. A portion of the socket is shown in section on a larger scale in Fig. 4, the details of our improved attachment being clearly disclosed. Fig. 5 is a sectional view, taken on the line 5-5 of Fig. 4.

10 represents a lamp socket of any well known form, having a metal shell or casing 11, a helically corrugated contact socket 12, and an interposed insulating sleeve 13.

The attachment of our invention comprises a ring-shaped body 15 having a laterally projecting key socket lug 16, an insulating ring 17, a pair of ears or clips 18, and a pawl lock 19.

The ears or clips 18 extend in an axial direction from the insulated surface of the ring 15 to which they are secured and are cylindrically curved. Each clip is preferably provided with an extruded lug 21 having transverse corrugations which are adapted to coöperate with the corrugated surface of the contact socket 12.

The pawl lock 19 is disposed in a recess 25 in the insulated surface of the ring 15 and is pressed against a shoulder 26 of the ring by a spring 27. It is so formed that when it is in engagement with the shoulder, a sharp cutting point 28 extends radially inward so as to prevent the backward movement of a base or plug which is inserted in the socket as hereinafter explained.

The key socket lug 16 is hollow and a pin 29 which is fitted into the pawl lock 19 at one end is disposed within it.

The arrangement of parts is such that a socket wrench or key 30 may be readily inserted in the hollow projection 16 and fitted onto the end of the pin which may be triangular or square in section, the lock 19 being released by merely turning the key in opposition to the spring 27. The lock is free to be swung out of the way in one direction and the arrangement of parts is such that this can be readily accomplished by the plug or base as it is inserted in the usual way, the lock acting as a ratchet in permitting an advance movement of the base but absolutely preventing a backward movement of the base or plug such as is necessary in removing the same.

Projecting from the side of the shank of the key is a lug 31 which when the key has been turned to release the pawl lock may be pushed up into a recess 32 cut in the lower edge of the socket 16 to hold the pawl in its unlocked position against the action of spring 27 so that the operator may have both hands free to unscrew the lamp from the socket.

As clearly shown in Figs. 1 and 5, the extruded lugs 21 are cut from the ears of which they form parts and have diamond-shaped ends 21 which are bent inwardly so that their points tend to dig into the helically corrugated outer walls of the con-

tact socket 12 and prevent the attachment from turning with the lamp base 40 or other plug which may be inserted in the socket. The edges of the ears are curved outward 5 as at 23 to engage the insulating sleeve 13 for the same purpose.

The attachment may readily be applied to any socket of the usual form by merely forcing the ears or clips 18 between the 10 helically corrugated exterior walls of the socket contact 12 and the insulating sleeve 13. The insulating ring 17 which covers the recess 25 of the ring 15 constitutes a stop and engages the outer edge of the shell or 15 casing 11 as clearly shown in Fig. 4. This outer casing or shell is therefore electrically separated from the attachment and consequently is not connected to the electrically active parts of the socket through any of 20 the metal parts of the attachment.

Structural modifications will be effected within the spirit and scope of our invention and we intend that only such limitations be imposed as are indicated in appended 25 claims.

What we claim is:

1. An attachment for contact sockets comprising a member having curved ear projections adapted to be forced into a socket, and 30 means for preventing rotary movement of the attachment and releasable means for preventing the removal of a base or plug after it has been inserted in the socket.

2. An attachment for contact sockets comprising a member having curved ear projections adapted to be forced into a socket, and having means for preventing rotary movement of the attachment and means for preventing the removal of a base or plug without 40 interfering with its introduction into the socket.

3. An attachment for contact sockets comprising a member having curved ear projections adapted to be forced into a socket 45 longitudinally, means on said projections for preventing rotary movement of the attachment, and a pawl lock adapted to be released by a suitable key for preventing the removal of a base or plug which has 50 been inserted in the socket.

4. An attachment for contact sockets comprising a member having curved ear projections adapted to be forced into a socket and having means for preventing rotary movement 55 of the attachment, a pawl lock, a spring arranged to press said pawl into locking position, a key for moving the lock out of locking position, and means for holding the key and the lock against the action 60 of the spring.

5. An attachment for contact sockets comprising a ring-shaped body having a laterally projecting key socket lug, a pair of cylindrically curved ears or clips adapted 65 to be inserted between the usual insulation

and the outer walls of a contact socket, and having means for preventing rotary movement of the attachment and a pawl lock mounted in said ring and extending into the opening within the ring. 70

6. An attachment for contact sockets comprising a ring-shaped body having a laterally projecting key socket lug and a pair of cylindrically curved ears or clips adapted to be inserted between the usual insulation 75 and the outer walls of a contact socket, and having means for preventing rotary movement of the attachment a pawl lock mounted in said ring and extending into the opening within the ring, a shoulder for limiting rotation of the pawl lock in one direction, and a spring for yieldingly holding the lock projection against rotative movement in the opposite direction. 80

7. An attachment for contact sockets comprising a ring-shaped body having a laterally projecting key socket lug and a pair of cylindrically curved ears or clips adapted to be inserted between the usual insulation 85 and the outer walls of a contact socket, and having means for preventing rotary movement of the attachment a pawl lock mounted in said ring and extending into the opening within the ring, a shoulder for limiting rotation of the pawl lock in one direction, a 90 spring for yieldingly holding the lock projection against rotative movement in the opposite direction, and a pin secured to said pawl lock and extending into said key socket projection, the outer end of said pin being shaped to receive a suitably formed releasing 95 socket key. 100

8. An attachment for contact sockets comprising a member having curved ear projections adapted to be forced into a socket, and having means for preventing rotary movement of the attachment a pawl lock pivotally supported in said member at the side thereof and having an outwardly extending pin, the end of said pin being shaped to receive a key, a spring arranged to press said pawl into locking position, a key socket surrounding the pin, the edge of said key socket being provided with a recess, a key arranged to engage the pin to move the pawl 110 out of locking position, and a lug projecting from the key and adapted to be moved into said key socket recess when the key has turned the pawl out of its locking position to hold said pawl out of its locking position against the action of the spring. 115

9. An attachment for contact sockets comprising a member having curved ear projections adapted to be forced into a socket longitudinally, extruded pointed lugs projecting from said ears adapted to engage a metallic portion of the contact socket, the edges of said projections being curved outwardly to engage another part of the socket, a pawl lock pivotally supported in said member at 120 125 130

the side thereof and having an outwardly extending pin, the end of said pin being shaped to receive a key, a spring arranged to press said pawl into locking position, a key socket surrounding the pin, the edge of said key socket being provided with a recess, a key arranged to engage the pin to move the pawl out of locking position, and a lug projecting from the key and adapted to be moved into said key socket recess when the key has turned the pawl out of its

locking position to hold said pawl out of its locking position against the action of the spring.

In witness whereof, we have hereunto set our hands in the presence of two subscribing witnesses, this 5th day of May, 1914.

ROBERT V. MILLER.
JOHN ARVID MOLIN.
